UNITED STATES PATENT OFFICE.

ELAM B. WINGER AND OSWALD E. WINGER, OF FREEPORT, ILLINOIS.

WINDMILL.

SPECIFICATION forming part of Letters Patent No. 425,841, dated April 15, 1890.

Application filed August 31, 1889. Serial No. 322,568. (No model.)

To all whom it may concern:

Be it known that we, ELAM B. WINGER and OSWALD E. WINGER, residents of Freeport, in the county of Stephenson and State of Illinois, have invented certain new and useful Improvements in Windmills; and we do hereby declare the following to be a full, clear, and exact description of the invention, such as will enable others skilled in the art to which it pertains to make and use the same.

Our invention relates to improvements in windmills of that class in which both vane and wind-wheel support are pivoted to a central standard, the normal position of the wind-wheel being approximately at right angles to the line of the vane, and the parts being so arranged and connected that the swinging of the wind-wheel out of its normal position raises the vane.

The invention is fully described, explained, and claimed in this specification, and shown in the accompanying drawings, in which—

Figure 1 is a perspective view of our improved windmill. Fig. 2 is a top plan of the working parts thereof. Fig. 3 is a similar view of those parts of the mill lying below a horizontal plane passed through the line XX, Fig. 1. Fig. 4 is a vertical section through the line YY, Fig. 2; and Fig. 5 is a vertical section through the line ZZ, Fig. 3.

In these views, A is a windmill-tower of ordinary construction.

B is the top plate of the tower, and C is a vertical standard journaled near its middle in the top plate B and at its foot in a support b, secured to the timbers of the tower, Fig. 1.

On the standard C, immediately above the top plate, is loosely mounted a revoluble ring D, provided with horizontal gudgeons d, and on these gudgeons are pivoted the front ends of two castings d', whose rear ends clasp and are fastened to the mid-rib E of a vane of ordinary construction, the vane being thus connected with the standard by a universal joint allowing it to swing either vertically or horizontally. Immediately above the ring D is a second ring F, rigidly secured to the standard by means of a key or set-screw and provided with two integrally-formed extensions G G', approximately at right angles to each other,

the extension G supporting a horizontal box or journal inclosing an ordinary wind-wheel shaft g, on which is rigidly mounted a wind-wheel spider g', and the extension G' being provided at its outer end with a pulley-block g'', whose use is hereinafter set forth. The wind-wheel shaft G and vane E are approximately parallel to each other, but are not in the same plane, the wind-wheel shaft being set at one side of the vertical plane of the vane, in order that the wind may more readily swing it from its normal position toward the vane, and the rings D F are formed with stops d'' f, adapted to limit the relative rotation of the two parts. Both these features of construction are well known in mills of this class and are only mentioned descriptively.

On the top of the standard C is rigidly mounted a ring or cap H, provided with an arm H', lying in a vertical plane slightly oblique with reference to the plane of the wind-wheel shaft, and a wire W is fastened to the free end of the arm H' and connects it with a point on the mid-rib E of the vane at a considerable distance from the standard C, thus supporting the weight of the vane. A brace h, fastened at one end to the extension G and at the other end to a suitable projection on the cap H, braces the frame of the mill and counterbalances the weight of the vane with that of the wind-wheel and the parts which support it. A chain I is fastened to the mid-rib of the vane at a point about as far from the standard C as the pulley g'', already referred to, and is carried from the vane about said pulley g'' and over a pulley h', mounted on the cap H, and passes thence downward through the standard to the foot of the tower, the office of this chain being to draw the wind-wheel out of the wind by swinging the extension G' and the wind-wheel-supporting parts in the direction indicated by the arrow in Figs. 2 and 3. The end of the wire W may be secured to the free end of the arm H' in any desired manner; but we prefer to fasten it adjustably in the manner illustrated in Figs. 2 and 4, in which h'' is a transversely-slotted extension of the arm, and H'' is a block resting on said extension and provided with an annular flange h''', and with a neck extending downward into the slot

in said extension. A loop in the end of the wire W encircles the block and rests upon the flange h'' , and a cap h''' , resting upon the block and projecting over the wire, is secured by means of a bolt passing through the block and cap, and having at its lower end a head of a diameter greater than the width of the slot in the extension h'' . The block may be secured at any desired point in the slotted extension, thus varying slightly the angle of the wire W to the vane.

It is evident that when the mill is in operation and the vane is held in any given plane by the force of the wind the swinging of the wind-wheel and its supporting parts in the direction indicated by the arrow in Figs. 2 and 3 will swing the arm H' in the same direction, and thereby raise the free end of the vane, and any variation of the angle of the wire to the vane will change the initial effect upon the vane of such swinging of the arm H' . It is also evident that the return of the wind-wheel to its normal position, after having been moved therefrom in the manner described, will also return the arm H' to the position shown in the drawings, and will thereby permit the free end of the vane to drop down to its normal position, the weight of the vane being thus the regulating force which tends to hold the wheel in its normal position and to return it thereto after it has been moved out of such position.

On the inner end of the wind-wheel shaft g is rigidly mounted a crank K , provided with a crank-pin k , and on this crank-pin is pivoted the lower end of the pitman P , whose upper end is pivoted on a gudgeon k' , projecting from a vertically-reciprocating slide S , conforming to the outer surface of the standard C . The inner face of the upper end of the pitman rests against a boss or shoulder s , formed upon the slide at the base of the gudgeon k' , and the inner face of the pitman at about its middle point rests against a guide s' , also formed on the slide and lying in the vertical plane of the shoulder s . The upper end of the pitman is secured against accidental displacement in the manner hereinafter described, and the shoulder s and guide s' hold the lower end of the pitman in contact or very nearly in contact with the face of the crank K , and thereby dispense with the necessity of securing the lower end of the pitman in place by any means other than the plain cylindrical crank-pin k passing through it.

Within the standard C is a second slide S' , conforming to the inner surface of the standard and provided with vertical webs T , extending through and sliding in a slot c in the standard and resting against the inner face of the outer slide S , and lugs t , formed on the webs T , extend into corresponding sockets in the slide S and prevent independent vertical movement of the two slides $S S'$. A half-round or half-oval pump-rod R rests

against the inner concave face of the slide S' , and suitable bolts pass through the two slides and the pump-rod and bind them firmly together, the bolts being so placed as to lie within the slot c of the standard C . One of these bolts passes axially through the gudgeon k' and holds in place a cap k'' , of greater diameter than the gudgeon, the projecting edges of the cap extending over a portion of the pitman P and preventing accidental disengagement of the pitman from the gudgeon.

We are aware that many of the features of the mill illustrated and hereinbefore described are old and in common use in the art, and such features are shown and described merely as parts of the operative mechanism including our invention. We therefore disclaim any novelty except such as is set forth in and covered by the following claims, to wit:

1. The combination, with the standard C , of the vane E , connected with the standard by a universal joint, the wind-wheel-supporting casting $F G$, rigidly fastened to the standard, the cap H , fastened to the standard and provided with the arm H' , the wire W , connecting the vane with said arm, and the brace-rod h , connecting the wind-wheel support with the cap H , whereby the weight of the vane and of the wind-wheel and its support are sustained from opposite sides of the standard and counterbalance each other, substantially as and for the purpose set forth.

2. The combination, with the tubular standard and the wind-wheel-supporting casting rigidly fastened thereto, of the wind-wheel shaft g , journaled in said casting, the crank K , fastened to the inner end of the wind-wheel shaft and provided with the crank-pin k , the slide S , conforming to the outer surface of the standard and provided with the gudgeon k' , the pitman P , connecting the crank-pin k and gudgeon k' , the slide S' , lying within the standard and rigidly connected with the external slide S , and the pump-rod R , fastened to said internal slide, substantially as and for the purpose set forth.

3. The combination, with the tubular standard C , formed with the vertical slot c , of the slides $S S'$, lying, respectively, outside and inside of the tubular standard and rigidly bolted together, one of said slides being provided with a web extending through and sliding in the slot c , and also with lugs entering corresponding sockets in the other slide, and the external slide being provided with a gudgeon for receiving the end of a suitable pitman, substantially as and for the purpose set forth.

4. The combination of the tubular standard C , external and internal slides $S S'$ and pump-rod R , said slides and pump-rod being rigidly bolted together, and one of said slides being provided with a projection extending through the slot in the standard and engaging the other of said slides, substantially as and for the purpose set forth.

5. The combination, with the standard C, having the slot c, of the slide S, formed with the gudgeon k' and guide s', the pitman P, pivoted on said gudgeon and secured in place 5 thereon, substantially as shown and described, the slide S', formed with the web T and lugs t, the pump-rod R, attached to the slide s', and bolts fastening together said slides and pump-rod, substantially as and for the purpose set forth.

In testimony whereof we have signed this

specification in the presence of two subscribing witnesses.
